INTERCOMMUNICATION SYSTEM FOR BOWLING ALLEYS**Maurice L. Goldstein, Chicago, Ill.****Application July 29, 1953, Serial No. 370,920.****1 Claim. (Cl. 179—2)**

This invention relates to bowling alleys and particularly to the improvement of acoustic conditions therein.

It is usual in bowling halls to provide a bowling counter, in supervisory relation to the various alleys. In spite of such provision it was unavoidable, heretofore, that loud talking or shouting went on from time to time, between bowlers and pin boys or pit attendants. In the larger bowling halls, with numerous alleys in simultaneous operation, this resulted in great noise and confusion. This unsatisfactory condition progressed in direct proportion to the size of a bowling establishment, thereby imposing definite limits upon the growth of such establishment.

Automatic pin-setting devices were tried in order to remedy such conditions. However, they, in turn, have definite limitations and shortcomings. In smaller communities, it is hard to find qualified mechanics and maintenance men for the highly specialized, electronic apparatus required to spot, memorize and re-set individual standing pins. Even with the best service and maintenance, an automatic pin-setter can perform only standard operations, and even that only with some direct or indirect supervision and aid by machine mechanics and front attendants.

I have invented a bowling alley arrangement capable of combining the quiet and dignity of well-constructed and well maintained automatic set-up with the versatility and simplicity of a manual set-up. This new arrangement operates with equal efficiency regardless of size and capacity. It makes the bowling hall construction more flexible than it was in the past.

In this new system direct intercommunication between bowlers and pin boys or vice versa is eliminated. For this purpose, a new use is made of the bowling counter and a new and more flexible location is made available for it; not necessarily in a position from which the attendant can visually observe the alleys. The new system provides that, whenever a bowler wishes to communicate with his pin boy, or vice versa, he can do so, but only through the counter. All messages are routed through a master instrument especially provided on the counter for this purpose. The instrument can be operated; for instance, by a vending attendant, or by an office clerk, either of whom thereby becomes a supervisory operator, receiving messages from the pit and from any of the bowlers' bays and relaying proper messages, in suitable form, to the bays and the pit. The supervisor can also originate calls to either end of any of the alleys. On the other hand, he can only be spoken to from one of these points at any one time, and only when he, the supervisor, has suitably connected his instrument with such point. Visible and/or audible call signals can be sent from these several points to the master instrument; and said instrument can store and retain any number of such call signals, simultaneously, while positively allowing only one single talk-listen connection, to one single calling point, at any one time.

By this multiple signaling, single communicating ar-

2

rangement, greatly improved conditions have been established in bowling alleys; conditions which are better than those heretofore existing either in conventional manual-setting or automatic-setting alleys; also better than anything obtainable with conventional intercommunication systems of otherwise comparable type.

The operation is expedited by certain particular features of the master instrument and comprehensive arrangement; particularly, a novel arrangement of call signal elements and call control elements for two ends of each alley in close proximity to one another, on an open selector and indicator board.

The details in this and other respects will be understood more clearly upon a study of the full disclosure of a preferred embodiment, to be described hereinafter. It will be understood that a number of specific details are provided in this preferred embodiment which can be modified without leaving the gist and scope of this invention, to be defined by the claim appended at the end of this description.

In the drawing:

Figure 1 is a diagrammatic assembly view of the major units utilized in the present invention.

Figure 2 is a plan view of a bowling establishment utilizing the present invention.

Figure 3 is a cross section through the establishment of Figure 2, along lines 3—3.

Figure 4 is a similar cross section, along lines 4—4.

Figure 5 is a fragmentary view of the system of Figure 1, more detailed electrically but more diagrammatic mechanically.

Figure 6 is another fragmentary view of the same system, still more detailed electrically and still more schematic mechanically.

Figure 7 is a fragmentary view generally similar to Figure 6 but showing another part of the system; and

Figure 8 is still another similar view, completing the diagrammatic representation of the electric system.

Referring first to Figure 1: The manual bowling establishment as shown comprises a plurality of alleys 11, 12, 13, 14, 15, 16. At the pin end A of each alley the bowling pins are provided. The other end B of each alley is equipped with the usual bay. A pit P extends along and partly below the ends A to provide operating room for the pin boys who replace the proper bowling pins according to well-known rules.

Each alley is interconnected with a master control instrument 17 which has two principal parts: An amplifier and control unit 18 and an alley and station selector unit 19. Conductors, generally shown at 20, are provided to separately interconnect each end of each alley with the selector unit 19, for signalling and communication by and through the amplifier and control unit 18.

For this purpose the conductors 20 connect the master instrument 17 with a series of voice pick-up and speaker units 21, 22, 23, 24, 25, 26, also comprising push-button signal switches and thereby forming outlying stations, at the bay ends of the respective alleys 11 to 16; and with similar outlying stations 31, 32, 33, 34, 35, 36, provided at other ends A of the different alleys, within the pit P (Fig. 2).

The voice pick-up and speaker openings of both groups of instruments 21, 31, etc., face in the same direction, that is, in the direction from the bay B to the pin end A. They are so adjusted as to be operable within their respective, limited bay or pit areas, forming only parts of the alley. For instance, a bay speaker and pick-up unit 21 is loud enough to be heard distinctly in and adjacent the respective bay but not in the pit, and sensitive enough to pick up ordinary talk from adjacent the bay

but not from the pit. It will be realized that the picking up of messages from a bowler or pin boy, by a pick-up instrument relaying the message to the master instrument, requires only a much lower voice level than does the direct communication between the two ends of a relatively long bowling alley. This is so not only because of the lesser average distance between the speaking person and the direct speech receiver, but also because of the fact that, by interposition of the suitably arranged master instrument, suitable amplification can be applied, with proper individual adjustment for the bowlers' bay and the pit and with further general adjustment depending upon the overall condition of the bowling establishment and the noise level therein.

Referring now to Figure 2, it will be noted that the conductors 20 comprise two cables 20A and 20B extending respectively along the pit ends A and bay ends B of the series of bowling alleys 11, etc. Both cables converge to the instrument 17. This instrument is shown as standing on the counter 27 provided in the usual supervisory location 37. As noted above, it could also be located elsewhere, even remotely of the alleys.

Of course, the same platform which conventionally provides for the counter 27 can also be used to provide for a general entrance 38, an office 39, a checkroom 40, a ball room 41, shops, restaurants, and the like; such rooms, as shown, may be disposed around the long and narrow sides of the alleys 11, 12, etc., along with the area 37. The possibility of locating the instrument 17 anywhere makes the construction of the bowling hall or establishment more flexible and potentially more income producing.

Otherwise this present bowlers' hall can be built as usual. For instance, the usual stands 42 for spectators and/or waiting bowlers can be provided adjacent the bay ends B of the alleys 11, etc.

The ceiling 43 of the building is desirably equipped with a sound deadening construction, such as a reflecting arch 44, it being unnecessary and undesirable in accordance herewith to provide acoustic interconnection between the ends A, B of the bowling alleys.

Referring now to Figure 5: The selector instrument 19 contains a pair of call indicator or signal light assemblies 51, 61 for the alley 11 and a similar pair 52, 62 or 53, 63, etc., for each other alley 12, 13, etc. It will be noted that the call indicator light assemblies of each pair 51, 61, etc., are closely juxtaposed; as shown, superposed above one another. The series 51, 52, etc., is provided for the bay ends B of the different alleys, while the series 61, 62, etc., is provided for the pin ends A of the different alleys.

Closely adjacent each call indicator light assembly the instrument 19 has a lever handle 71, 81, etc., forming part of a manual multiple selector switch, whereby the correlated switch handles 71, 81, etc., for the two ends of each alley are juxtaposed similarly to the respective light stations.

Thus the front of the master instrument 17 effectively reproduces the alleys on a small scale. For instance, station 21 is represented by a signal unit 51 and switch handle 71, etc.

In the drawing, the instrument portion 91 relating to the alley 11 is shown in some detail, whereas the other similar portions 92, 93, 94, 95 and 96, belonging to the other alleys 12 to 16 respectively, are shown only in general outline. Those parts visible in front of the instrument are most clearly shown in Figure 1, while Figure 5 also shows the major electric interconnections of the different instruments 51, 61, 71 and 81.

As schematically shown in Figure 5, the master control unit 18 controls each outlying instrument 21, 31, etc., through a corresponding switch 71, 81, etc., with the further aid of a relay switch 101, 111, etc., thereby also controlling the respective call indicator light stations 51, 61, etc. Connection between each outlying station 21, etc., and the corresponding switch and indicator

units 71, 101, 51 is shown as being made through a suitable set of conductors; three such conductors being shown and used in the present instance and being interconnected with the respective instrument portion 91, etc., by suitable connectors 121, 131, etc.

Referring now to Figures 6 to 8, it will be noted that each outlying station 21, etc., has the usual voice pick-up and speaker cone, voice coil and permanent magnet, together with a single pole signal push button switch. It will further be noted that these coils and switch elements of each station 21, etc., are connected with the corresponding unit 91, etc. in the master instrument, through a three-terminal connector 121, etc.

Figure 7 shows only one of these instrument units 91, and that only so far as necessary to indicate the connections to and from one outlying station 21. Any desired number of instrument units 91, 92, etc., with a pair of indicator lights and a pair of selector switches each, can be provided; the number of such units being equal with the number of bowling alleys to be served by the system. Additional units similar to the unit 91 (or in some cases not arranged in pairs), may be provided, of course, in outlying stations 28, 29, 30, etc., in such locations as the office 37 (Fig. 2), pin boys' quarters Q (Fig. 3), etc. All units 91, etc., have multiple connections, parallel with one another, with a series of bus wires between the control and selector portions 18, 19; these bus wires being identified by numerals 1, 3, 4, 5, 6, 7, and 9 respectively.

Details of these interconnections will best be described in conjunction with the operation of the system, which is as follows:

Normally all call switches of the outlying stations are open and all call indicator lights on the master instrument are de-energized and dark. This condition is shown in the drawing.

Referring now to Figures 6, 7 and 8, and assuming that a bowler in alley 11 momentarily closes the signal switch of the outlying station 21, this establishes a momentary electric circuit from the terminal 1 of a source of direct current SD through conductor C25, the uppermost pole of the manual switch 71, conductor C1, connector 121, conductor C2, the signal switch in 21, conductor C3, connector 121, conductor C4, the coil of the signal relay 101 and conductor C5 to a second and grounded terminal 6 of the source SD. This energizes the coil of the signal relay 101, thereby closing the three normally open switches of this relay. The lowermost switch establishes self-holding or locking circuit for the relay through the conductor C25, upper pole of switch 71, conductors C1, C6, relay coil conductor C5, so that the relay switches remain closed even after the reopening of the momentary call switch in the station 21.

Visible and audible signals are established through the signal relay 101 as follows, upon the energization of the relay which has just been described. A source of alternating current SA has a terminal 9 connected by conductor C7 with the uppermost switch in the signal relay 101 and further connected, in the closed condition of this relay, by a further conductor C8 with one terminal of a red incandescent lamp R in the signal light unit 51. The other terminal of the lamp, by conductor C9, is connected with the opposite terminal 7 of the source SA. Thus the closing of the switches of relay 101 results in lighting up of one of the red signal lights in the front panel of the master instrument 17; this particular signal light forming part of the instrument unit 91 connected with the alley 11. The attendant can now see that a bowler in that alley wishes to talk with him. The attendant is also alerted to the call by an audible signal, caused by a buzzer B in the master instrument. For this purpose the terminal 7 of the source of alternating current SA is connected with one terminal of the buzzer while the other terminal of the buzzer through a bus 5 and conductor C10 is connected with one side of the

middle switch in the signal relay 101; said switch, when closed, making connection to conductor C11 and thereby, through the conductor C7, to the other terminal 9 of the source of alternating current SA. In this manner, when any one of the red signal lamps is energized, this also actuates the common buzzer B, while avoiding feed-backs between signal and lamp units.

In order to establish a talk-listen connection with the outlying station 21, the attendant must now reverse the manual switch 71 directly above the lighted signal light 51R.

In the condition established by this operation, the voice coil of the outlying station 21 acts as a source of current at audio frequency. One terminal C2 of this coil is connected, through the connector 121, conductor C1 and further conductor C12 to the third pole of the manual switch 71 (counting from the top) and thereby to a conductor C13 connecting it with the bus 3. This bus has a branch C14 containing a conventional condenser and leading to one of the two normally closed terminals of a double pole, double throw talk-listen switch TL. Through said switch terminal and its normally closed pole, further connection is made to a conductor C15 leading to the primary coil of an input transformer IT. The other side of this primary coil is connected with the grounded bus 6.

Audio frequency currents, induced in the secondary coil of the input transformer IT are fed through an input volume control rheostat IR (the control knob of which is also shown in Figure 1) to the grid of a first amplifier triode T-1. The plate voltage of this triode is impressed in the usual manner upon the grid of a second amplifier triode T-2, and the plate voltage of that tube is impressed in the usual manner upon the control grid of a final amplifier tube shown as a pentode T-3. The plate current of that tube feeds the primary coil of an output transformer OT, the secondary coil of which is connected, by a conductor C16 and the normally closed terminal of the second pole of the talk-listen switch TL and conductor C17, with an adjustable output volume control rheostat OR (the control knob of which is also shown in Figure 1). This rheostat by a conductor C18 feeds the earphone E of the master control telephone instrument T, the other terminal of which is grounded at 6. Thus the attendant can now hear what the bowler in alley 11 speaks into the cone of his instrument 21.

In order to establish a connection whereby the attendant can answer the bowler in alley 21, a manual talk switch TS is provided in the telephone instrument T of the master station (the handle of which is also shown in Figure 1). When the attendant depresses the handle of this switch and thereby closes the switch, this energizes the coil of the talk-listen relay TL through the terminal 1 of the source of direct current SD, the branch conductor C19, the relay coil, the conductor C20, the switch TS, and the grounded wire 6. This reverses the poles of the talk-listen relay TL, thereby breaking the connection for talk from the outlying station, previously established as explained, and establishing instead a connection wherein the upper pole of the talk-listen relay switch TL connects one terminal of a small microphone battery MB through the conductor C15 with the input transformer; the other side of the battery MB being connected with the microphone M and thereby with the ground 6. The output transformer now is connected through the conductor C16 and the lower pole of the talk-listen relay switch TL with the bus wire 3; and this bus, by means of the aforementioned connections C13, 71, C-12, C1, C2 leads to the voice coil of the outlying instrument 21. This coil now acts as a load. It is grounded through conductor C21, connector 121, conductor C22, the lowermost pole of the manual switch 71, conductor C5 and grounded bus 6.

Accordingly, when the attendant has reversed the manual switch 71 of the instrument unit 91 belonging to

the alley 11 and particularly to the bay 21, he can listen to talk from said bay when he releases the talk switch TS and can talk with said bay when he presses this switch.

It will be noted that at this time as before, in fact at all times, the bowler cannot electrically communicate with the outlying station 31 at the pin end of his alley, or with any other part of the system, but only with the master instrument.

The fact that the proper, selective talk-listen connection has been established between the master instrument and the outlying, calling station 21, as described, is desirably evidenced at the master instrument itself in order to avoid confusion as to whether and where a connection has been made. For this purpose additional poles are provided in the manual switch 71. The aforementioned uppermost pole of that switch has been reversed together with the two lowermost poles. Since the connection for the energization of the red signal light R51 and the buzzer B had been made through this uppermost pole, these instruments are now deenergized; the red light is "out" and the buzzer is silent. On the other hand, the terminal 9 of the source of alternating current SA is connected by a conductor C23 with a second pole of the manual switch 71 (counting from the top as always) and through said pole and a conductor C24 to one terminal of a green indicator lamp G in the light station 51. The other terminal of that lamp is interconnected with the second terminal of the red lamp R, which, as described before, is connected by conductor C9 with the second terminal 7 of the source of alternating current SA. Thus the establishment of the proper talk-listen connection is indicated by the disappearance of the red signal light and the appearance of the green indicator light directly below the same, identifying the signalling station, and the establishment of talk-listen connection with it.

Furthermore, it will be noted that the uppermost pole of the manual switch 71 has double-throw connections. In the lowered condition established during the talk-listen connection, this pole connects the direct current terminal 1 through a conductor C25 with a conductor C26 leading to bus 4. This bus leads to a B-voltage relay BR, the other terminal of which is grounded to 6 and which now closes a relay switch BRS interconnecting the center tap of a second direct current source coil SD2 with the grounded wire 6. This second source of direct current SD2 comprises a rectifier tube interconnected with the amplifier tubes T1, T2 and T3 so as to insure proper voltage conditions for talk. The details of such interconnections are known to the art and need not be described herein.

It will now be seen that a complete cycle of inter-communicating operation, for instance from 21 to 31, is effected by simple and rapid electric steps, with great efficiency from the standpoint of bowling alley management.

For instance, assume that a bowler in the bay of alley 11 wants to have the pin boy set the pins in some special manner. For this purpose the bowler himself or anybody in his party can signal the attendant by momentarily depressing his signal switch 21. The attendant can immediately see the proper red light R51. Practically at once he can reverse the corresponding manual switch 71, take the telephone receiver T, press the talk-switch lever TS and acknowledge the signal through the microphone M, intermediate amplifier and circuits as described, and speaker 21. All this can be done in about a second. As soon as the attendant releases the talk-switch lever TS the bowler can tell him, at ordinary low voice level, what to tell the pin boy. This the attendant can do promptly by returning switch 71 to normal condition while turning the directly subjacent switch 81 (see Figure 4) to talk-listen position. In this new position, with both lights of the calling unit 51 being off and the green light of the receiving unit 61

now being on, the attendant converses with the pin boy, using his talk-switch TS as before.

Other examples of how the system can be utilized will occur to persons skilled in the bowling art. In every instance, necessary and proper messages are indirectly but easily relayed from the bay to the pit and vice versa. Direct messages between these points, which tend to become improper at times in the excitement of the game, are safely eliminated. Visual supervision from a bowling center is no longer necessary, although it remains possible.

A number of modifications can be applied in manners which will be found to be obvious upon a study of this disclosure.

I claim:

An intercommunication system for bowling alleys, 15 comprising a plurality of paired outlying sub-stations, each pair consisting of an alley bay sub-station and an alley pit sub-station; each one of said substations including a signal switch and a voice receiver-transmitter; a central control station comprising juxtaposed pairs of signal relay switches, manually operable multiple selector switches, signal annunciators and acknowledgment annunciators; each of said juxtaposed pairs consisting of alley bay sub-station switches and annunciators and alley pit sub-station switches and annunciators; all the 20 alley bay sub-stations switches and annunciators being linearly arranged in a first line; all the alley pit sub-station switches and annunciators being linearly arranged in a second line parallel to said first line and in corresponding sequential position thereto so that the sub-station 25 switches and annunciators associated with each bowling alley are in the same relative position at the central
